UNITED STATES PATENT OFFICE.

HERBERT HOLDEN, OF BOSTON, MASSACHUSETTS.

APPARATUS FOR PROTECTING VESSELS AGAINST AERIAL ATTACKS.

Application filed July 3, 1928. Serial No. 290,091.

The present invention relates to an apparatus for protecting vessels, such as warships and the like, from damage by bombs dropped from aeroplanes during an aerial attack, and aims to provide a novel and improved apparatus of this character having a relatively large member adapted to be rotated at a relatively high rate of speed constructed in an inverted cone-shaped formation and arranged over the vital parts of the vessel, such as the engine room, and adapted to direct or throw bombs dropped thereon into the water away from the vessel prior to the exploding thereof.

Another object of the invention is the provision of an inverted cone-shaped member adapted to be rotated at a high rate of speed composed of a frame supporting block of resilient material, said resilient material aiding in the throwing of bombs away from the vessel, as well as aiding in the preventing of the operation of the explosive caps of the bombs when striking the rotatable member.

A further object of the invention is the provision of a slidable, rotatable, inverted cone-shaped member arranged over the vital parts of a vessel, said rotatable member being adapted to slide upwardly on the shaft on which the same is mounted when rotated at a high rate of speed and arranged in a manner for permitting the dropping thereof on the shaft when engaged by a bomb, thus increasing the efficiency of the rotatable member in preventing the explosion of the bomb.

A still further object of the invention is to provide a pair of nets arranged at the forward and rearward sides of the rotatable, inverted cone-shaped member so as to protect the bow and stern of the vessel, said nets being resiliently mounted so as to permit the same to give when a bomb is dropped thereon or thrown thereon by the rotatable member, thus aiding in preventing the explosion of a bomb.

It is also an object of the invention to provide an apparatus of the above indicated character, which will be thoroughly efficient and practical in use for protecting a vessel against the explosion of bombs dropped thereon during an aerial attack.

With the foregoing and other objects in view, which will be apparent as the description proceeds, the invention resides in the construction and arrangement of parts, as hereinafter described and claimed, it being understood that changes can be made within

the scope of what is claimed, without departing from the spirit of the invention.

The invention is illustrated in the accompanying drawings, wherein:

Figure 1 is a side elevation of a battle ship showing my improved apparatus applied thereto,

Figure 2 is a top plan of the same,

Figure 3 is a vertical section through the apparatus.

Referring to the drawings, the numeral 10 designates a vessel, and as a matter of illustration a warship is shown, having a bow 11, central portion 12, at which point the engine room and other vital parts of the vessel are arranged, and a stern 13.

In carrying out the invention, the numeral 15 indicates an inverted cone-shaped member which is mounted upon a shaft 16 rotatably mounted in a base bearing 17 and an elevated bearing 18 supported by a housing 19. The base bearing 17 and the housing 19 are supported upon the deck of the vessel at the central portion 12 thereof. On the lower end of the shaft 16 is a bevel gear 20 which meshes with another bevel gear 21 secured to the drive shaft of an electric motor or dynamo 22 also mounted upon the deck of the vessel. It can be seen that when the electric motor or dynamo 22 is operated, the shaft 16 will be rotated in the bearings 17 and 18.

The inverted cone-shaped member 15 is constructed of a metallic frame 23 which supports a plurality of resilient blocks 24 of rubber or similar material. The frame 23 has a plurality of annular flanges 25 thereon arranged in spaced relation from each other which overlap the edges of the resilient blocks 24 at their upper and lower sides, while a plurality of radially extending overlapping flanges 26 engage the other sides of the resilient blocks 24 in order to hold said resilient blocks in proper position. By referring to Figures 1 and 2 of the drawings, it can be seen that the radiating flanges 26 radiate from the apex of the inverted cone-shaped member as they extend downwardly to the main base flange 27 of the frame 23. From the foregoing, it can be seen that the resilient blocks 24 practically cover the entire outer surface of the inverted cone-shaped member and that it is only at the meeting edges of the various resilient blocks that the metallic flanges 25, 26, and 27 are arranged. The outer surfaces 100

of the resilient blocks 24 are gradually rounded, as at 28, the purpose of which is to eliminate

inate to a great extent a direct contact of a bomb dropped upon the inverted cone-shaped member.

At the upper end of the shaft 16 the same is slotted, as at 29, and a pin 30 carried by the upper end of the inverted cone-shaped member extends through the slot so as to cause the inverted cone-shaped member to be rotated upon rotation of the shaft 16. The frame 23 of the inverted cone-shaped member has a relatively long sleeve 31 arranged centrally thereof which extends practically the entire height of the inverted cone-shaped member so as to properly support the same on the shaft 16. At the lower end of the sleeve 31 is a socket 32 into which upstanding pins 33 engage when the inverted cone-shaped member is in its lowermost position on the shaft 16. On the upper end of the pins are arranged coil springs 34 for relieving the pins 33 of shocks when the inverted cone-shaped member slides downwardly on the shaft 16. It can be seen that by providing the driving connection by means of the element 20, the inverted cone-shaped member will be rotated with the shaft 16, yet the same is permitted to slide thereon. When the shaft 16 is rotated at a high rate of speed, the inverted cone-shaped member will rise on the shaft due to the high speed of rotation thereof and in case a bomb is dropped on said member, the latter will be permitted to drop slightly so as to break the efficiency of contact of the bomb with the inverted cone-shaped member. On the upper end of the shaft 29 is arranged an enlarged head 35 for limiting upward sliding movement of the inverted cone-shaped member.

Over the stern 11 and bow 13 of the vessel are arranged frames 36 and 37 which support metal mesh material 38 of sufficient strength for supporting a bomb dropped thereon or a bomb thrown from the rotatable member 15 and having a mesh that will prevent fragments of bombs exploded in the air from dropping on the deck of the vessel. The frames 36 and 37 are supported by a plurality of posts 39 arranged adjacent the corners of the frames and attached to the same through coil springs 40 so as to resiliently mount the frames having the screen material thereon.

In operation, the inverted cone-shaped member 15 is rotated at a high rate of speed, which will cause the same to rise on the shaft 16. In case a bomb is dropped on the rotating inverted cone-shaped member, the same will be quickly thrown therefrom into the water away from the vessel due to the high rotation of speed of the inverted cone-shaped member. To aid in the efficiency of directing bombs away from the vessel the resilient blocks 24 are provided which will cause a quick rebound of the bombs, and in case they explode, they will be away from the inverted cone-shaped member at the time of ex-

plosion so as to avoid causing damage to the inverted cone-shaped member. Should bombs from the inverted cone-shaped member be thrown upon the net at the bow and stern of the vessel or be dropped directly thereon, the same will yield in order to prevent exploding of the bombs, or in case the bombs are exploded thereon, the same will be held away from the hull of the vessel so as to avoid damaging same. By having the nets resiliently mounted, the bombs when dropping will naturally rebound to a certain extent and be slightly away from the nets so as to eliminate damage to a great extent.

While the invention is illustrated and described in connection with a vessel, it is to be understood that the same may be efficiently used in connection with protecting buildings or like property against damage by bombs dropped from aeroplanes or the like.

Having thus described my invention, what I claim as new is:

1. An apparatus of the character described in combination with a vessel, comprising an inverted cone-shaped member arranged above the vessel and rotated at a high rate of speed, and nets arranged at the opposite ends of said inverted cone-shaped member.

2. An apparatus of the character described in combination with a vessel, comprising a rotatable shaft, an inverted cone-shaped member carried by said rotatable shaft and adapted to rotate therewith, said rotatable member being of a diameter substantially the same as the width of the beam of the vessel.

3. An apparatus of the character described in combination with a vessel, comprising a rotatable shaft, an inverted cone-shaped member carried by said rotatable shaft and adapted to rotate therewith, said rotatable member being of a diameter substantially the same as the width of the beam of the vessel, and nets arranged at opposite sides of the inverted cone-shaped member.

4. An apparatus of the character described in combination with a vessel, comprising a rotatable shaft, an inverted cone-shaped member carried by said rotatable shaft and adapted to rotate therewith, said rotatable member being of a diameter substantially the same as the width of the beam of the vessel, supports carried by the vessel, yieldable means arranged on said supports, and nets attached to said yieldable means so as to yieldably support said nets.

5. An apparatus of the character described in combination with a vessel, comprising a rotatable shaft, an inverted cone-shaped member slidably mounted on said shaft and fastened thereto so as to rotate therewith, means for limiting downward sliding movement of said inverted cone-shaped member on said shaft, and means for limiting upward sliding movement of said inverted cone-shaped member on said shaft.

6. An apparatus of the character described in combination with a vessel, comprising a rotatable shaft, an inverted cone-shaped member slidably mounted on said shaft and fastened thereto so as to rotate therewith, means for limiting downward sliding movement of said inverted cone-shaped member on said shaft, means for limiting upward sliding movement of said inverted cone-shaped member on said shaft, and resilient means located at the means for limiting downward movement of the inverted cone-shaped member so as to absorb shock when said inverted cone-shaped member slides downwardly on the shaft. ¹⁵
7. An apparatus of the character described in combination with a vessel, comprising an inverted cone-shaped member arranged over the central portion of the vessel, means for rotating said inverted cone-shaped member at a high rate of speed, and nets arranged on planes adjacent the lower surface of the inverted cone-shaped member over the bow and stern of the vessel. ²⁰

HERBERT HOLDEN.
